US00D892142S

(12) **United States Design Patent** (10) Patent No.: **US D892,142 S**
Clifford et al. (45) Date of Patent: **** Aug. 4, 2020**

(54) **DISPLAY SCREEN WITH GRAPHICAL USER INTERFACE FOR A MULTIMODE SURGICAL CONSOLE**

(71) Applicant: **Stryker Corporation**, Kalamazoo, MI (US)

(72) Inventors: **Steven Thomas Clifford**, Byron Center, MI (US); **Anna-Karin Soederstroem**, Morgan Hill, CA (US); **Sarah Garcia**, San Jose, CA (US)

(73) Assignee: **Stryker Corporation**, Kalamazoo, MI (US)

(**) Term: **15 Years**

(21) Appl. No.: **29/696,602**

(22) Filed: **Jun. 28, 2019**

Related U.S. Application Data

(63) Continuation of application No. 29/602,200, filed on Apr. 28, 2017, now Pat. No. Des. 856,345.

CLAIM

The ornamental design for a display screen with graphic user interface for a multimode surgical console, as shown and described.

DESCRIPTION

The FIGURE is a front view of a display screen with graphic user interface for a multimode surgical console showing our new design.

The broken lines showing an electronic device illustrate environmental subject matter, whereas the broken lines showing a display screen and elements of the graphical user interface illustrate portions of the article. No subject matter depicted in broken lines form part of the claimed design.
